J. W. ROBERTS, A. P. BREWSTER & B. BRYSON.
COMBINED TENSION AND STOPPING DEVICE FOR SEWING MACHINES.
APPLICATION FILED MAY 27, 1913.

1,164,752.

Patented Dec. 21, 1915.

UNITED STATES PATENT OFFICE.

JOHN WILLIAM ROBERTS, ARTHUR PERCY BREWSTER, AND BOYD BRYSON, OF
PASSAIC, NEW JERSEY.

COMBINED TENSION AND STOPPING DEVICE FOR SEWING-MACHINES.

1,164,752.

Specification of Letters Patent.

Patented Dec. 21, 1915.

Application filed May 27, 1913. Serial No. 770,162.

To all whom it may concern:

Be it known that we, JOHN W. ROBERTS and ARTHUR P. BREWSTER, citizens of the United States, and BOYD BRYSON, subject of the King of England, respectively, residing at Passaic, in the county of Passaic, and State of New Jersey, have invented certain new and useful Improvements in Combined Tension and Stopping Devices for Sewing-Machines; and we do hereby declare the following to be a full, clear, and exact description of the invention, such as will enable others skilled in the art to which it appertains to make and use the same, reference being had to the accompanying drawing, and to figures of reference marked thereon, which form a part of this specification.

This invention relates to an improved means for stopping sewing-machines when tension on the goods of the machine is relaxed, and is of the class of machine illustrated in the patent to Roberts and Brewster, issued October 29, 1912, No. 1,042,602, and the patents to Roberts, Brewster and Bryson, issued Feb. 18, 1913, No. 1,053,647, this present invention, however, being an improvement over the prior ones inasmuch as the tripping means is directly connected to the goods under tension, and the same mechanism operates to give the tension to the goods and when said tension is relaxed, operates to trip a clutch or similar mechanism to disconnect the machine from its source of power.

The device is particularly adapted for sewing-machines when used in series or in numbers in factories where a single operator takes care of a number of machines, in which case it is necessary to have the machine stopped automatically when the goods that is being fed to the machine is exhausted. When the end of the goods arrives at or near the tensioning means, the tensioning means is released and operates a trip which in turn releases a clutch, this stopping the machine by disconnecting it and the operator will quickly note that the machine is stopped and renew the supply of goods fed to the machine. The clutch mechanism is normally operated to release the machine automatically from its source of power and is locked in position by a suitable locking means when it is in position to connect the machine with its source of power, and a trip, which releases the locking means, is held in

operative by its resting at one end on the goods, thus acting both as a tension means and a trip. The tension is supplied by suitable weight, or in some cases a different mechanism might be employed for supplying the means of operation of the device for both the tensioning and the tripping. It will be understood, however, that the operating means are the same for both ends of the device so as to supply both the tension and the tripping. The tripping means is also designed to hold the locking member of the clutch in its tripped or released position so that the parts are held in their unlocked positions and there is no opportunity for accidental setting of the clutch to start the machine.

There are different manners in which this invention can be applied, but the preferred form is embodied in the accompanying drawing, in which—

Figure 1 is a view of the clutch and the tensioning and tripping means, the machine being shown in dotted outline. Fig. 2 is a top view with the end of the tripping lever and an end of the locking member of the clutch.

In the drawing we have not gone into detail as far as the sewing mechanism of the sewing-machine is concerned, simply illustrating in dotted outline the frame 10 mounted on a base 11, the base being in the form of a table, and these tables in practice are arranged with a slight incline, although they may be otherwise disposed if desired.

A tripping shaft 12 is operated by means of a pulley 13 when the clutch 14 is operative and is adapted to be released therefrom when the clutch is inoperative, the machine being supplied with the usual form of fly or handwheel 15 for adjusting the needle-bar or the like when desired. The clutch 14 is operated by a suitable clutch-arm 16, of which there are a number of types, but one type is shown, this being pivoted at 17 and having a free end 18 on which is a pin 19. The pin 19 rests against a setting-rod 20 pivoted at 21 and being adapted to be operated by a suitable handle 22. When the handle 22 is pushed down the setting-rod 20 swings the pin 19 in until the end 23 of the setting-rod sets in a groove 24 in the locking arm 25. The locking arm, either by spring action or by gravity, is normally pressed against the end 23 of the setting-arm 20, and the parts as shown in full lines in Fig. 1 are

locked so that the clutch is operative and is held so that it can not be swung by the spring 26 fastened to the clutch and to a suitable point on the frame, this releasing means having a normal tendency to swing the clutch to a position where it disconnects or permits the disconnection of the machine from its source of power. The locking arm 25 projects beyond the setting-rod 20 and is 10 provided with a suitable projection 27, usually in the shape of a pin which projects from the locking arm and is in the path of the tripping means to be hereinafter described. The preferred embodiment of the 15 tripping means comprises a rocking structure which is held in one position by the tension of the goods and is rocked in the other position by suitable operating means, such as a weight, the same means acting 20 directly on the goods and on the clutch release, according to which one is inoperative, that is, when one is inoperative, the other one is operative.

The goods 28 in passing to the machine 25 is passed over any suitable set of guides or bars, but in the drawing we show but one bar 29 over which the goods is passed on its way to the sewing mechanism (not shown). Resting on the goods 28 to give it a tension 30 is the end 30 of a stem 31 the stem being adjustable by means of the collar 32 on a bar 33. The bar 33 is arranged in a block 34 which swings on a pin 35, which pin is in a fixed support which is not shown, but 35 which may be any part of the structure on which the machine is mounted. The bar 33 projects beyond the block 34 and is provided with a suitable weight 36 which is kept from pulling the block 34 downward 40 to rotate the pin 35 to which it is fastened by reason of the end 30 of the stem 31 being held up by the goods, and thus in itself supplying a tension to the goods. Fastened to the pin 35 is a suitable lever or arm 37, 45 the lever having an inclined portion 38 thereon, the face of which, when it swings, being adapted to engage the pin or projection 27, since the pin is arranged to be in the path of the inclined end of the tripping lever. The operating portion at the end of 50 the tripping lever is preferably recessed at its end as at 39, this being usually accomplished by simply bending over the end 40 to form a hook. It will be evident that 55 when tension on the goods is relaxed by reason of the end of the goods having reached or being in the act of approaching the end 30 of the stem 31, the weight 36 becomes inoperative and the bar 33 swings 60 downward and at the same time swings the tripping lever. The inclined face 41 of the

tripping lever engages the pin 27 and raises it. This lifting of the pin of course carries the locking arm 25 with it and as soon as the locking arm is raised the notch 24 releases the end 23 of the setting-rod 20 and the spring 26 pulls the clutch-arm so that the clutch is released and the machine is stopped. The movement of the weight and of the tensioning and tripping means is 65 limited by reason of the recess 39 acting as a stop for the pin 27 and being stopped in turn thereby so that the locking arm is held in its raised position whereby accidental dropping of the locking arm is impossible, 70 and the swing of the bar 33 and its attachment is also limited.

This invention makes it necessary to place the goods under tension before the machine is started, as the placing of the tension device on the goods must precede the securing of the clutch locking arm, since until this tension is applied by raising the bar 33, the trip will continue to hold the locking arm in raised position. This prevents a thoughtless operator from starting the machine without placing the goods under tension, and therefore the turning out of "seconds" is minimized, since the tension must be established before the locking arm of the clutch 90 is released.

It will be understood that details of construction may be changed in this invention without departing from the scope of the claims, and we reserve to ourselves the right 95 to make such minor changes as may be necessary.

Having thus described our invention, what we claim is:—

A sewing-machine to which goods are fed 100 under a tension, a clutch for connecting and disconnecting the machine from its source of power, a swinging lever with an inclined portion, a movable locking means for holding the clutch operative, a projection on the 105 locking means and in the path of the inclined portion when the lever swings, a swinging bar connected to the lever, means for suspending the bar from the goods to give the goods a tension and to support the 110 bar so as to hold the lever in inoperative position, and a stop in the inclined portion to engage the projection.

In testimony, that we claim the foregoing, we have hereunto set our hands this 23rd 115 day of May 1913.
